UNITED STATES PATENT OFFICE.

ARTHUR E. BLOFIELD, OF NEW YORK, N. Y.

COMBINATION TOOL AND BEVEL-GAGE.

1,103,344.

Specification of Letters Patent.

Patented July 14, 1914.

Application filed May 25, 1911. Serial No. 629,384.

To all whom it may concern:

Be it known that I, ARTHUR E. BLOFIELD, a citizen of the United States, and a resident of New York city, borough of Bronx, county of New York, State of New York, have invented certain new and useful Improvements in a Combination Tool and Bevel-Gage, of which the following is a description:

10. My invention relates to improvements in a combination tool and bevel gage and my object is to provide a tool of this character, especially designed for the use of tool makers, mechanics and other artisans, which tool shall be simple and compact in construction, and capable of being readily and exactly adjusted.

My improved tool preferably comprises a bevel gage and protractor, a combination square and bevel, a depth gage, especially adapted for operating in holes of small section cut at an angle, and is also adapted for other uses, as will more fully appear in the following specification. My improved tool does not, however, necessarily embody all of the above mentioned functions.

Other objects of my invention are the combinations of parts and construction of elements hereinafter described in the following specification and particularly pointed out in the appended claims.

In order that a clearer understanding of my invention may be had, attention is hereby directed to the accompanying drawings, forming part of the specification and illustrating certain embodiments of my invention:

In the drawings, Figure 1 represents a plan view of one form of device embodying my invention; Fig. 2 represents a vertical section of the same taken on line 2—2 of Fig. 1; Fig. 3 represents a partial bottom plan view of the device, certain parts being removed for the sake of clearness; Fig. 4 represents a bottom view of the indicating dial with the indicating pointer mounted thereon; Fig. 5 represents a detail of construction; Fig. 6 is a cross section taken on line 6—6 of Fig. 1; Fig. 7 represents a detail of construction; Fig. 8 is an enlarged plan view of the dial and pointer, shown in Fig. 1; and Figs. 9 and 10 represent respectively a plan view and a perspective view of modified forms of dial and pointer.

Referring to the drawings, the device preferably comprises a stock 1 having up-

per and lower members 2 and 3, as shown in Fig. 2, both of which are formed with a longitudinal slot 4, as shown in Fig. 1. The blade 5 is provided in the direction of its length with the longitudinal slot 6 which preferably is provided with a circular enlargement 7 adjacent one end of the blade. The blade 5 is preferably mounted in such a manner as to permit rotation of the same with respect to the stock and also a sliding movement of the blade in the direction of its own length and in the direction of the length of the stock, as will be described. The dial plate 8 is suitably mounted to slide along the slot 4 of stock 1 with the blade, but not to rotate, and pointer member 9 is suitably mounted to rotate over the dial 8 to measure the angular movement of the blade 5 with respect to the stock. Preferably the dial 8 is provided upon its underside with a boss or projection 10, flattened on two sides to fit within the slot 4 of the upper member 2 of stock 1, so that the dial member may slide along the stock but not rotate with respect thereto. The pointer 9 is provided with a boss 11 mounted within a circular opening through the center of dial plate 8 and its boss 10. Boss 11 is cylindrical so far as it passes through boss 10 of dial plate 8, so that it may rotate freely with respect to the dial plate. The lower end of boss 11, however, is flattened on two sides, as indicated at 12, in Fig. 4. Blade 5 is positioned between the upper and lower members 2 and 3 of stock 1, with the flattened end 12 of boss 11 engaging within the slot 6 of blade 5 so that blade 5 may slide in the direction of its length upon boss 11, but angularly. Movement of blade 5 about the axis of boss 11, gives pointer 9 a corresponding angular movement. Boss 11 and the pointer are provided with a passageway therethrough, axial of the boss, through which opening is passed the pin 13, which is screw-threaded upon its end, as shown at 14 in Fig. 2. Pin 13 is provided with a head 15 adapted to bear against the underside of member 3 of the stock, which head 15 has a boss 16 formed upon the upper side thereof flattened on two sides, as shown in Fig. 5, and adapted to be slidably engaged within the slot 4 of the lower member 3 of the stock, so that pin 13 may slide along the stock with the blade 5, dial plate 8, and connected parts, but cannot ro-

tate with respect to the stock. The wing nut 17 is mounted upon the screw threaded periphery of the upper end of screw 14 and preferably has a spiral spring 18 mounted within a recess formed in the same, surrounding pin 14 and pressing upon the upper surface of the boss of pointer 9. When the pointer and blade 5 have been adjusted to any desired angular position, nut 17 may be screwed down to clamp the parts in the adjusted position.

The manner of graduating dial plate 8 and the coaction with the same of the pointer are features of my invention. As indicated more particularly in Fig. 8, I prefer to graduate the dial plate adjacent to its periphery into degrees by tens, as shown at 19, indicating figures or indicia 19' preferably being placed upon the dial plate adjacent to these division marks. As shown in the drawings, I have two positions marked zero, with the degree marks running by tens from zero to 90 degrees in each direction. The pointer member 9 is triangular in shape, that is, it has straight edges 20 and 21 upon its sides, which edges are radial, or would pass, if prolonged, through the axis of rotation of the pointer at the center of dial 8. The distance between the outer ends of sides 20 and 21 of the pointer is the same as the distance between the indicating characters 0—0, and the parts are so arranged that when the pointer is positioned with the two zero marks in alinement with its edges 20 and 21, blade 5 is exactly parallel to stock 1. The edges of pointer 9 are preferably beveled as shown, and marks 19 are radial to the center of rotation of the pointer. When pointer 9 is moved to the left, referring to Figs. 1 and 8, until the left hand edge 20 of the pointer comes into alinement with the thirty degree graduation of the dial to the left of the dial, referring to Fig. 8, the edge 22 of blade 5 makes an angle of thirty degrees with the upper edge of stock 1 and the edge 23 of the blade makes an angle of thirty degrees with the lower edge of the stock 1. When pointer 9 is moved to the right until the right hand edge 21 of the pointer comes into alinement with, for example, the thirty degree mark, that portion of edge 23 of blade 5 which appears as the upper part of the blade in Fig. 1, will make an angle of thirty degrees with the lower edge of the stock, and that portion of edge 22 of the blade which is shown below the stock in Fig. 1, will make an angle of thirty degrees with the upper edge of the stock, and correspondingly, if the pointer is set in alinement with any other of the graduation marks 19.

The dial plate, according to the form of my invention being described, is marked off into ten concentric rings, *a*, *b*, *r*, *d*, *a*, *f*, *g*, *h*, *i*, *k*, by the equally spaced circles *a'*, *b'*, *c'*,

d', *e'*, *f'*, *g'*, *h'*, *i'*, *k'*, the graduations 19 being marked radially in the annulus *k* between the circles *k'* and *i'*. These circles or arcs of circles are all struck from the axis of rotation of pointer 9 as a center. The inner nine rings are also divided by equally spaced radial graduations 24, the graduations of each ring extending from the inner to the outer circle thereof and the marks 24 of each circular series being ten degrees apart. The 78 graduations 24 of each ring are one degree in advance of the corresponding graduations of the next smaller ring. That is, the marks of the smallest ring *a* represent one degree, 11 degrees, 21 degrees, etc., the graduations 80 of ring *b* represent 2 degrees, 12 degrees, 22 degrees, etc., the graduations of ring *c* represent 3 degrees, 13 degrees, 23 degrees, etc., and the same for all of the circles in both directions from the zero marks. That is, the 82 angular distance between the zero and ten degree lines or between any of the adjacent graduations 19 is divided into ten equal parts, spaced apart from each other at equal radial distances from the center. The result 90 of this construction is that the dial plate can be extremely small and compact without the confusion which would result if it were attempted to place the whole of 180 or 360 degrees adjacent the periphery of so small a 95 dial plate as I prefer to use. The pointer 9 has concentric arcs *m*—*m*—*m* formed across the same struck from the axis of rotation of the pointer as a center, which arcs correspond to and are of the same radii as 100 arcs *a'*, *b'*, *c'*, etc., of the dial plate, the pointer accordingly being divided into segments of rings *r*—*r*—*r*, etc., corresponding to rings *a*, *b*, *c*, etc., of the dial plate, and indicating characters 1 to 9 are preferably 105 marked within these rings on the pointer, the figure 1 being marked within the innermost ring *r* corresponding to the smallest ring *a* of the dial. Accordingly, when it is desired to get a reading of one degree in 110 either direction, the edge 20 or 21 of the pointer member is moved slightly from the zero position until the edge adjacent the figure 1 comes into line with the nearest graduation upon the dial. If it is desired to 115 get a reading of, for example, 23 degrees in either direction, the corresponding edge of the pointer is brought into line with the graduation adjacent the figure 20 upon the periphery of the dial and the pointer is then 120 moved a slight further distance until the same edge of the pointer adjacent the figure 3, upon the pointer, is brought into alinement with the first mark in the ring *c* of the dial.

If greater accuracy in reading the device is desired, the construction shown in Fig. 9 may be employed, in which pointer 9 is provided with a series of small holes 25 therethrough, one in each of the rings *r* and the 130

dial is provided with corresponding circular series of holes 26, one of which corresponds to each angular position of the pointer. A small pin 27 may be provided which is adapted to fit exactly within holes 25 and 26, which may be passed through the corresponding holes in the pointer and the dial to accurately aline and hold the pointer in any desired position to which it may be set. Furthermore, it is not essential that the graduations of the dial be made upon the face thereof.

For some uses, a construction such as that shown in Fig. 10 might be preferable, this figure illustrating a construction in which the dial member 8' is of a much more considerable thickness than the dial 8, shown in the previous figures, dial member 8' being graduated upon its periphery in the same manner as has been described in connection with the marking upon the face of the dial 8, of Fig. 8. In this case, the pointer member 9' has an extension 28 in the form of a portion of a hollow cylinder which rests upon and is adapted to rotate around the periphery 29 of member 8'. Such construction is of advantage where the reading of the angle is more conveniently made from the edge and where the added thickness of the dial member is not objectionable. In this case, of course, the series of holes 25 and 26 with the corresponding pin 27 may also be used if desired.

When, for any reason, it is desired to rotate blade 5 without moving the pointer, the enlarged portion 7 of slot 6 of blade 5 may be brought into position surrounding the boss 11 of the pointer. Preferably blade 5 is provided with a beveled end 30 as shown, which is formed at 60 degrees or at any desired angle with the edge 23 of the blade. Also preferably the blade 5 carries a small graduated scale 31 which is slidably mounted adjacent one edge as the edge 23 of the blade. This small scale is slidably mounted in any desired manner as by the dove-tail construction shown at 32 in Fig. 2, and may be extended in either direction beyond the end of blade 5. This small scale may be extended into conical or angular holes of small section into which blade 5 could not pass.

Preferably my device is provided with an attachment whereby the straight edge 33 may be adjustably secured to stock 1. A screw 34 having a head 35 provided with two pins 36, preferably tapered, may be extended through the upper and lower members of stock 1 and a corresponding opening in straight edge 33, the nut 37 being mounted upon the upper screw-threaded periphery of screw 34 to clamp the parts in adjusted position, a bracket 38 upon the face of stock 1 having a circular flange 39 extending above the annular flange 40 upon nut 37 to hold the latter in position. Blade or straight

edge 33 may be provided with two pairs of holes 41 at right angles with each other through either pair of which the prongs 36 of head 35 may be passed, to secure blade 33 in position, either at right angles to stock 1 or parallel thereto. Or, of course, any number of holes 41 may be provided, spaced in any desired manner, so that blade 33 might be given any desired angular position with respect to stock 1. When blade 33 is positioned parallel to stock 1, beveled edge 42 of blade 33 is positioned across stock 1, and either edge of blade 5 may be brought in contact therewith to quickly position the blade at whatever angle is represented by edge 42, without setting the protractor. When straight edge 33 is set at right angles to the stock, the tool becomes a square.

The lower edge of the upper face of stock 1 may be graduated as shown at 43, the graduations beginning at a point in line with the inner edge of blade 33 when the same is positioned at right angles to the stock. By this means the device may be used as a pair of calipers, blade 5 and blade 33 being adjusted into contact with the opposite sides of any object to be measured, and the distance between the same read on scale 43. If scale 43 is used, dial 8, which is preferably beveled adjacent its lower edge, should be cut back a slight distance from its lower edge to permit the reading of scale 43.

It should be understood that my invention is not limited to the exact details of construction shown, but that my invention is as broad as is indicated by the accompanying claims.

Having now described my invention what I claim as new and desire to protect by Letters Patent is:

1. In a device of the character described, the combination with a dial member, of a pointer mounted concentrically with said dial member, to rotate with respect thereto, said dial member being divided into tens of degrees along each of ten concentric arcs struck from the axis of said pointer as a center by short lines intersecting said arcs, each of said lines being at an angular advance of one degree beyond the adjacent degree line of the nearest smaller arc, said dial member also carrying indicia adjacent the degree lines of the outer arc, and said pointer carrying indicia at radial distances from its axis corresponding to the radial position of said degree lines of the arcs of said dial member other than said outer arc, said indicia being adapted to indicate the angular position of said pointer when the same is rotated.

2. In a device of the character described, the combination with a dial member of a pointer mounted concentrically with said dial member to rotate with respect thereto, said dial member being divided into units

105

110

115

120

125

130

of circular measures spaced along said dial, and in such a manner that the radial lines of the concentric arcs struck from the axis of said pointer, will indicate the angular position of the dial, said dial being carried by a pointer, which pointer is provided with a dial adjacent the marks spaced along the outer edge of the dial, and with a radial line 5 outermost edge, and said pointer carrying the dial, will indicate the angular position of the dial at the same radial distance from the axis as the marks of the other arcs, the dial being adapted to indicate the angular position of the pointer when brought into alignment with any of said radial lines and the radial marks,

3. In a device of the character described, the combination with a dial member of a circular shape, having a pointer mounted to move over said member, of a dial pointer, of a dial member having a circular periphery, said member being divided into graduations, the dial pointer being mounted to move over the dial member, the dial pointer having a circular measure by marks placed at different radial distances from the axis of said dial pointer, and said pointer being triangular in shape, with radial side edges adapted to be in close proximity to the radial lines of the dial member, the dial pointer being the only pointer on the dial member.

4. In a device of the character described, the combination with a dial member of a pointer mounted to move over said member, said member being divided into duplicate series of marks of circular measure, and said pointer having two edges so located with respect to said dial division marks that one edge is adapted to be brought into alignment with the edge of a mark when the said member is rotated.

This instrument signed and witnessed
this 15th day of May 1932.
